PHILIPPE ARNATI, OF PARIS, FRANCE.

KEYLESS COMBINATION-LOCK MECHANISM FOR PADLOCKS, DOOR LOCKS, AND THE LIKE.

Application filed January 27, 1925, Serial No. 5,053, and in France February 6, 1924.

The present invention relates to a combination lock for the keyless operation of all padlocks, door locks and the like, consisting in principle of a set of cams having a single notch which are combined with independent wheels which are toothed only upon a part of their periphery, said cams acting upon a lever or like pivoted member controlling the latch of the said lock, whereby the said member can only be displaced for the disengagement of the latch when the notches in all the cams are brought into line by the suitable rotation of milled heads in such manner that a predetermined combination of figures is realized.

Another feature of the invention consists in the fact that the combination can be changed at will without being obliged to take the mechanism apart, due to a suitable connection between each cam and its corresponding toothed wheel, and thus after the cam has been held by means of a pointed instrument, for instance a needle, which is inserted through the mechanism which has been preliminarily brought into the open position, each of the toothed wheels can be displaced by a chosen angle with reference to its corresponding cam.

According to a certain form of construction, the said connection is obtained by the use of a flat spring whereof one end is secured to the face of the cam and the other, having the shape of a pawl, is engaged with one of the teeth of the wheel mounted upon the said cam.

The following description with reference to the appended drawings which are given by way of example sets forth the said invention.

Fig. 1 shows the mechanism as applied to a padlock, and in the closed position.

Figs. 1^a, 1^b and 1^c are detail views of the mechanism.

Fig. 2 is a view of the lock mechanism, in the open position.

Figs. 3 and 4 are sections on the lines X—X and X¹—X¹ of Figs. 1 and 2 respectively.

Fig. 5 shows the operation of the locking mechanism.

Fig. 6 shows a modification, representing the interior of the padlock.

Fig. 7 shows a toothed wheel.

Fig. 8 is a section on the line X—X of Fig. 7.

Within the casing *o* of the said padlock, three toothed wheels *a* *b* *c* are mounted in the coaxial position and are respectively secured to the milled heads *a*¹ *b*¹ *c*¹. In the constructional form herein represented, the milled head *b*¹ is keyed to the shaft *b*² which is secured by a pin to the milled head *b*¹. Each of the toothed wheels *a* *b* *c* comprises a toothed portion *a*² *b*² *c*² and a smooth portion *a*³ *b*³ *c*³; each wheel is secured to a respective cam *A* *B* *C* in which are formed the notches *A*⁴ *B*⁴ *C*⁴; the said cams and wheels are disposed upon a common center line X—X, Fig. 3.

Each of the toothed wheels is connected with its respective cam by means of a spring strip, as shown at *A*¹ for the cam *A*, one end *A*² of the said strip being secured to the cam, while the other end *A*³ is engaged with one of the teeth of the portion *a*². The same disposition prevails for the other combinations *b* *B*, *c* *C*, as shown in Fig. 5; the connecting springs for the latter combinations are not shown in the figures for the sake of clearness, but the arrangement is the same as for the spring *A*¹, Fig. 1.

The cams *A* *B* *C* cooperate on their periphery with a common rod *e* secured to the end of the lever *f* which is pivoted at *g* and whereof the other end *f*¹ is pivoted to the latch *h*. Upon the said latch is mounted the strap *i* whose cheeks are apertured at *j*, Fig. 4; like apertures are formed at *o*¹ in the front plate of the casing *o*, and also at *o*² *o*³ *o*⁴ in the respective cams *A* *B* *C*.

The said toothed wheels, with their cams, are held in position by the spring strips *a*⁵ *b*⁵ *c*⁵ which are separately disposed, as shown in Fig. 5, and whereof one end is secured to the side of the casing, as shown at *a*⁶ in Fig. 1 for the spring *a*⁵, the other end *a*⁷ *b*⁷ *c*⁷ being engaged after the manner of a pawl with a tooth of the cooperating part *a*² of the wheel.

The operation is as follows:

The padlock being in the open position, Fig. 2, all the cams will occupy a position such that the notches *A*⁴ *B*⁴ *C*⁴ will coincide with a suitable rod *e* which is controlled by a spring *e*¹ and is thus engaged with the notches *A*⁴ *B*⁴ *C*⁴; the arm *f* will have the position shown in Fig. 2 in which the latch *h* is drawn back and is thus disengaged from the staple *h*¹ of the curved arm of the padlock.

Each of the wheels a^3 b^3 c^3 has a determined angular position with respect to its corresponding cam A B or C; with reference to Fig. 5 it is observed that the fourth recess 5 or space between the teeth of the portion a^2 —starting from the smooth part a^3 and proceeding in the clockwise direction—will coincide with the notch A^4 ; the sixth recess is in coincidence with the notch B^4 ; the 10 seventh recess is in coincidence with the notch C^4 .

If the operation is commenced by bringing the wheel a into a position wherein the last recess 10 engages the pawl a^7 , Fig. 1^a, 15 the cam must be turned in the clockwise direction (arrow F) through the angle α in order to bring the notch A^4 into coincidence with the rod e ; this angle α corresponds to 4 teeth. In like manner, if the operation 20 is commenced by bringing the wheel b into a position wherein the tooth 1 engages the pawl b^7 , Fig. 1^b, the wheel must be turned through an angle β according to the arrow F^1 in order to effect coincidence between 25 the notch B^4 and the rod e . The angle β corresponds to 7 teeth.

If the operation is commenced by bringing the wheel c into a position such that the recess 1 engages the pawl c^7 , the cam C must 30 be turned through an angle φ , this angle corresponding to 8 teeth. It should be noted that the direction of the arrow F^1 in Figs. 1^a and 1^b is contrary to the direction of the arrow F in Fig. 1^a, since the knob or head a^1 controlling the wheel a , and the heads b^1 c^1 respectively controlling the wheels b 35 c , are disposed upon opposite sides of the padlock; in these conditions, the operation amounts to turning the said heads a^1 b^1 c^1 in 40 the clockwise direction.

If the padlock is closed, and the combination is mixed up by turning the three heads a^1 b^1 c^1 through any desired angle, 45 the padlock will now be in the locked position inasmuch as the rod e no longer coincides with the notches A^4 B^4 C^4 in the said cams; herein the smooth part of the cam impels the said rod and causes the lever f to pivot at g , thus bringing the latch h from the position which it occupied in Fig. 4 into 50 the position shown in Fig. 1 in which it will enter the staple h^1 .

Supposing that the figure representing the combination is for example 589, the mechanism can be released by proceeding as above indicated; the head a^1 is turned in order to effect coincidence between the smooth part a^3 and the end a^7 of the spring a^5 ; it will be an easy matter to take account of this 60 position, for upon a slight rotation of the head a^1 no clicking sound will be heard, and this sound will be heard only when the pawl a^7 engages a recess between two teeth or proceeds from one tooth to another. The 65 above-mentioned position, which may be

termed the inoperative position, can be readily found by a few trials, and the head a^1 is then turned so as to effect coincidence between the recess 10 and the pawl a^7 ; the cam 1 will now have the position shown in Fig. 1^a; it must now be turned through the angle α , or by 4 teeth, and this can be readily performed by counting 4 successive clicks, or in all 5 clicks, since the first combination figure is 5. I proceed in like manner by turning the head b^1 into the inoperative position and then turning it so as to effect coincidence between the pawl b^7 and the tooth No. 1 (the number 1 being counted from, the first click, Fig. 1^b); the cam B is then turned through an angle corresponding to 7 additional clicks, or in all 8 clicks, since 75 C is the second figure of the combination. In like manner, 9 clicks are produced by means of the head c^1 . At this time, the padlock will be in the unlocked position.

One of the features of the locking device according to the invention, consists in the fact that the combination can be changed at will without taking the device apart or removing the said wheels, such as is required in the known padlocks, and in my said device, the combination can be changed only when the mechanism is in the unlocked position, so that the padlock cannot be tampered with.

For this purpose, the mechanism having been brought into the unlocked position, a needle or a small nail is inserted into the holes o^1 o^2 o^3 o^4 and j ; thus holding the three cams in position. The three milled heads may now be turned so as to change the position of each cam relatively to its wheel, and this position can be readily ascertained by counting the number of clicks due to the movement of the pawl ends of the springs such as A^1 from one tooth to another.

Obviously, the said invention is not limited to the constructional forms hereinbefore described, and is susceptible of all desired modifications without departing from the spirit of the invention. In particular, I may combine any suitable number of toothed wheels, and may further dispose the milled heads upon one or both sides of the padlock. The plain part of the said wheels may be striated or slightly grooved or milled in order to obviate all slipping when the combination number comprises zero among the figures.

In the device hereinbefore described, each wheel comprises a smooth or roughened part which forms the inoperative (or zero) portion. But in virtue of the length of this portion, a combination comprising the zero figure cannot be employed, and some precautions must be taken in order to ascertain whether the said pawl has been brought upon this part.

This smooth portion of the wheel may be

dispensed with (Figs. 6, 7 and 8) by substituting therefor a suitable notch α^0 having a greater depth than the said recesses between the teeth, so that when the milled head is rotated it will be an easy matter to observe when the pawl drops into the said notch. I prefer to give to the latter a shape such that the milled head can be turned only in one direction, or according to the arrow (Fig. 7) as shown in the devices Figs. 6, 7 and 8.

Another advantage offered by this arrangement consists in the fact that the nine teeth of the wheel and the said additional notch are spaced in a uniform manner upon the periphery of the wheels, and the diameter of the latter can be accordingly reduced.

The connecting means between the cam and its corresponding toothed wheel may consist of a small strip spring or rod α^0 which is maintained by the milled head and is for instance disposed as shown in Fig. 8 in a slot formed in the said milled head, the curved end of the said spring engaging a hole or slot $A^1 A^2$, etc., formed in the cam.

What I claim is:

1. A combination lock device, comprising a plurality of juxtaposed cams, a toothed wheel adjacent each cam, a notch upon the periphery of each cam, elastic means connecting each wheel with its adjacent cam and providing for the angular displacement of each wheel upon its cam, an elastic member forming a pawl co-operating with each of the respective wheels and engaging one tooth, a latch, a movable member secured thereto, means whereby the said movable member together with the latch can be displaced only when the notches of all the cams are in line, independent external elements for the separate angular displacement of each wheel and cam unit to form the combination of figures as determined by the audible clicks produced by each unit.

2. A combination lock device, comprising juxtaposed cams, a toothed wheel adjacent each cam, a notch upon the periphery of each cam, a resilient pawl connecting each wheel with its corresponding cam, a resilient pawl co-operating with each wheel fixed at one end and having its free end engaging a tooth of the wheel the combined thickness of the pawls being of substantially the same thickness of a wheel, a latch, a pivoted lever connected therewith, a bar secured to the end of the said lever and in contact with the edges of the said cams, and milled heads for separately rotating the respective cam and wheel units, whereby the said notches in the cams may be brought into line.

3. A combination lock device, comprising juxtaposed cams, a toothed wheel adjacent

each cam, a notch upon the periphery of each cam, a spring connecting each wheel with its corresponding cam having one end secured to the wheel, each cam having an aperture cooperating with the outer end of the said spring, a resilient pawl co-operating with each wheel fixed at one end and having its free end engaging a tooth of the wheel, a latch, a pivoted lever connected therewith, a bar secured to the end of the said lever and in contact with the edges of the said cams, and milled heads for rotating the respective cam and wheel units, whereby the said notches in the cams may be brought into line.

4. A combination lock device, comprising juxtaposed cams, a toothed wheel adjacent each cam, a notch upon the periphery of each cam, elastic means connecting each wheel with its corresponding cam, means whereby each wheel may be angularly displaced, relatively to its corresponding cam without opening the lock when changing the combination of figures, an elastic element forming a pawl for each toothed wheel and engaging one tooth, a latch, a movable member connected therewith, means whereby the said movable member together with the latch can be displaced only when the notches of all the cams are in line, and means for the separate angular displacement of each wheel and cam unit.

5. A combination lock device, comprising a casing, juxtaposed cams mounted therein, a toothed wheel adjacent each cam, a notch upon the periphery of each cam, elastic means connecting each wheel with its corresponding cam, each cam having an aperture formed therein, a latch, a strap secured to the latter and having oppositely situated apertures formed in two branches thereof, said casing having a corresponding aperture formed therein and adapted to cooperate with the above-mentioned apertures whereby a needle may be inserted through the said apertures for the purpose of holding the wheels in the fixed position when the apertures in the said wheels have been placed in line, whereby the combination of figures can be changed by the angular displacement of the cams relatively to their wheels which are held in the fixed position, an elastic element forming a pawl for each wheel and engaging one tooth, a movable member secured to said latch, means whereby the said movable member together with the latch can be displaced only when the notches of all the cams are in line, and means for the separate angular displacement of each wheel and cam unit.

In testimony whereof I have signed this specification.

PHILIPPE ARNATI.
